UNITED STATES PATENT OFFICE.

JAMES M. BUTCHER, OF ST. LOUIS, MISSOURI, ASSIGNOR TO JAMES BANNERMAN AND HENRY H. CARR, OF ST. LOUIS, MISSOURI.

CHAIN JACK.

SPECIFICATION forming part of Letters Patent No. 774,231, dated November 8, 1904.

Application filed February 13, 1904. Serial No. 193,413. (No model.)

To all whom it may concern:

Be it known that I, JAMES M. BUTCHER, a citizen of the United States, and a resident of the city of St. Louis and State of Missouri, have invented a new and useful Improvement in Chain Jacks, of which the following is a specification:

My invention relates to lifting-jacks, and has for its principal objects to provide a rim-engaging chain jack that will securely engage the wheel-rim at the desired point, to provide a rim-engaging chain jack that will be caused to clamp the wheel-rim by the weight lifted by the jack, to provide an automatically-releasing rim-engaging hook for a chain jack, and other objects hereinafter appearing.

My invention consists in the parts and in the arrangements and combinations of parts hereinafter described and claimed.

In the accompanying drawings, forming a part of this specification, and wherein like symbols refer to like parts wherever they occur, Figure 1 is a view of a car-truck with my improved chain jack on one of the wheels in its initial position. Fig. 2 is a similar view showing the bearing-box raised by the jack after the truck has been moved to the left. Fig. 3 is a detail view, on an enlarged scale, showing the hook of my improved chain jack on a wheel. Fig. 4 is a vertical sectional view of the parts shown in Fig. 3, and Fig. 5 is a top view of the hook.

My improved chain jack consists of a chain 1 and a wheel-rim clamp 2, mounted on the end of the chain. The clamp 2 consists of a hook 3, conforming in shape to the outline of tread and flange of an ordinary car-wheel, as illustrated in Figs. 3 and 4. The shank 4 of the hook extends beyond the tread of the wheel and is provided with a slot 5, having its outer end wall 6 curved. A wedge 7 is mounted in the slot 5 and is provided with an eye 8, to which the chain 1 is attached.

In use the clamp 2 is placed on the rim of a wheel 9 at one side of its highest portion. The chain 1 is passed under the bearing-box 10, over the bottom bar 11 of the truck, and back over itself and under the bearing-box. It is pulled taut, and thus the wedge 7 is pulled

down so as to clamp the wheel-rim between 50 itself and the hook 3. The clamp is held securely in position by this adjustment. This arrangement is illustrated in Fig. 1. Then the car may be moved to the left, as illustrated, and the wheel will carry the clamp 2 upwardly. 55 The bearing-box 10 will be lifted with the chain, and after a slight movement of the car to the left the parts will occupy the position illustrated in Fig. 2. The weight of the car and the bearing-box 10 are lifted off the brass 12 60 and the car-axle, and the former may be easily withdrawn and replaced or another inserted. Then by moving the car to the right the load is gradually returned to the car-axle. When the wheel moves back beyond its initial position, the tension on the chain 1 ceases and the wedge 7 is no longer held down. Hence the clamp 2 is free to fall off the wheel and will be pulled to one side by the weight of the chain 1. The construction of the clamp prevents its 65 getting stuck on the wheel-rim and being carried down to strike and injure the brake.

Obviously my device is capable of considerable modification, and therefore I do not wish to be limited to the specific construction shown 70 and described.

What I claim as my invention, and desire to secure by Letters Patent, is—

1. A chain jack comprising a chain and a wheel-rim clamp having relatively movable 80 members, said clamp being arranged to be tightened by the load being lifted.

2. A chain jack comprising a wheel-rim clamp having relatively movable members, one of said members being a hook substantially 85 conforming to the shape of a wheel-rim, and a chain attached at only one end to said clamp.

3. A chain jack comprising a chain and a wheel-rim clamp having a hook substantially 90 conforming to the shape of a wheel-rim, and a relatively movable member arranged to engage the opposite side of the wheel-rim and clamp the same, said chain being connected to said clamp at one end only.

4. A chain jack comprising a chain and a wheel-rim clamp having a member arranged to engage one side of the wheel-rim and a rela-

tively movable member arranged to engage the opposite side of the wheel-rim, said chain being connected to one of said members to actuate said clamp.

5. A chain jack comprising a chain and a wheel-rim clamp comprising a hook arranged to engage one side of a wheel-rim and having a slotted shank, and a wedge arranged in the slot in said shank and arranged to engage the opposite side of the wheel-rim, said chain being connected to said wedge.

10. A chain jack comprising a chain and a wheel-rim clamp comprising a hook substan-

tially conforming to the shape of a wheel-rim and having a shank provided with a slot having its outer end wall curved, and a wedge arranged in said slot to bear upon said curved wall and the wheel-rim, said chain being connected to said wedge.

15. In testimony whereof I have signed my name to this specification in the presence of two subscribing witnesses.

JAMES M. BUTCHER.
